UNITED STATES PATENT OFFICE.

LOUIS LANE, OF HABANA, CUBA.

WINDOW.

Application filed August 23, 1922. Serial No. 583,750.

To all whom it may concern:

Be it known that I, LOUIS LANE, a citizen of the United States, and a resident of Habana, Cuba, have invented a new and Improved Window, of which the following is a description.

My invention relates to windows employing sliding sashes and the present invention is intended more particularly as an improvement on the invention forming the subject matter of United States Letters Patent No. 1,392,183, granted to me September 27, 1915.

The general object of the present invention is to improve the window frame jamb elements and the sash jamb elements or vertical side rails to effect line contact with each other as referred to in my patent above mentioned as well as to provide a form of frame jamb elements well adapted to coact with a novel weight box forming part of the present invention in association with a novel mode of hanging and arranging counterweights of the two sashes, the said sash weight box and the mode and means for hanging the weights being hereinafter fully referred to.

The nature of the invention and its distinguishing features and advantages will more clearly appear as the description proceeds.

Reference is to be had to the accompanying drawings forming a part of this specification, it being understood that the drawings are merely illustrative of one example of the invention.

Figure 1 is an elevation of the window embodying the present invention;

Figure 2 is a horizontal section on an enlarged scale as indicated by the line 2—2, Figure 1;

Figure 3 is a detail in side elevation with parts broken away and others in section showing the window structure adjacent the juncture of the sash weight box with the sill;

Figure 4 is a horizontal section on the line 4—4, Figure 3;

Figure 5 is a transverse vertical section on the line 5—5, Figure 3;

Figure 6 is a horizontal section of a modified form of sash weight box and the adjacent window frame jamb element.

In the illustrated example the window frame includes a top bar or frame head 10, a sill 11 and window frame jamb elements 12. The window frame jamb elements 12

are of channel form with transverse flanges 13 as in my patented construction above referred to but in the present construction the members 13 are in the form of intermediate members, there being formed on the jamb elements 12 terminal portions or flanges 14 directed outwardly in the general plane of the window, that is to say, toward the sash weight boxes hereinafter referred to. 65

Outer stops 15 as in my patented construction referred to are Z-shaped in cross section and secured by screws 16 or their equivalent. Similarly, inner stops 17 Z-shaped in cross section are employed and 70 one flange thereof secured by screws 18 or the like to the member 13 of frame jamb element 12. The stops 15, 17 are spaced 75 from the sides or main flanges of the jamb elements 12 to form with said sides channels 19 to receive the longer flanges 20 of sash jamb elements or vertical side rails 21 of the sashes A as fully described in my mentioned patent.

In the present construction, however, the 80 flanges 20 of the sash jamb elements 12 instead of extending in a direct line into the channels 19 are formed with oblique intermediate portions 20^a the arrangement serving to effect proper contact of the flanges 85 20 of the sash frame jamb elements with the frame jambs 12 and stops 15, 17. To increase the weather tight character of the structure vertical strips 22 may be applied to the members 13 of the frame jamb elements 12 between the same and the stops 15, 17 said strips 22 extending into the channels 19 and being returned for effective contact with the edges of the flanges 20 of the sash jamb elements 21. 95

In windows having vertically sliding sashes that are double-hung to counter weights sliding up and down in a weight-box at each jamb, it has been customary heretofore to make the weight-box at each 100 jamb of such size as to afford space for the two weights placed side by side, and to place both weight pulleys near the top of the window frame so that the weights by this arrangement travel up and down in their 105 respective portions of the weight-box passing each other as the sashes move up and down, with each weight using only a part of the vertical height of its compartment of the weight-box and with the result that 110 a large part of the total weight space provided in the box always remaining unused.

Such unused hollow portions of the weight box have many objectionable features and while in wooden frames there is very little objection to such form of construction as to cost, owing to the nature of the material employed in the construction of the boxes, in metal windows such boxes so made with double weight space area in cross section, become quite expensive and it is one purpose 10 of my invention to secure a substantial saving in this respect by using only a single compartment weight-box having an intermediate cross sectional area that the weights are disposed in said box in tandem or one 15 above the other in the same axial line and so that in which single box each weight travels only its predetermined portion of the vertical height of the weight box which is preferably extended down below the sill 20 level of the window a short distance in order to secure a sufficient weight travel distance and permit that the lower sash may be raised the height required to afford the greatest practical utility in ventilation in 25 the window.

A single compartment weight-box with the weight pulleys located as shown as near as practicable to the top of their respective sash and having a short extension of the 30 box below the sill in order that the upper sash may be lowered from one third to two thirds of its height down from the top and the lower sash raised upwards from the bottom about nine-tenths of its vertical height 35 fulfills practically all possible use needs of such windows with a manifest saving in cost while at the same time there is less liability of the window getting out of repair by weight interference inside the weight boxes while there is at the same time the 40 further advantage of a smaller and simpler and more durable window frame that will occupy less wall space than the present used double compartment box frame.

To accomplish this result of my invention I increase as compared to usual weight proportions the cross sectional area of the weights used relative to their length in order to reduce the height of box needed 50 for the vertical travel of the weights to each sash and in order to keep the cross section size of the weight somewhat close to the size of the inside of the weight-box for guiding purposes; while at the same time the box size is kept within limits to correspond 55 with the jamb size requirements of the window frame.

The sash weight box 23 shown is three-sided and at the open side thereof presents 60 terminal portions 24 overlapping the terminal flanges 14 of the frame jamb elements 12 to which they are suitably fastened. Each sash weight box 23 at that side disposed toward the interior of the room or 65 inner side of the window has doors or re-

movable panels 26 flanged to fit in channels 25 formed on the said box 23. Said doors are detachably secured as by screws 27. The box 23 is continued below the sill 11 as indicated at 123. To coordinate said box 23 70 and sill 11 the web or top of the sill (which sill is channel form in cross section) is cut near the ends to conform to the cross section of the frame jamb element 12, the latter being continued as indicated at 112 through 75 and below said sill. That portion of the web of the sill 11 lying outward of the frame jamb element 12 is cut as indicated by dotted lines, Figure 4, and turned downwardly against the sides or flanges of the 80 sill as at 28 and secured by bolts or rivets 29, thereby leaving a clear opening through the sill 11 to the box extension 123 for the movement of the lower sash weight below the sill as will appear. Angle pieces 30 are 85 laid against the weight of the sill 11 at the under side as clearly seen in Figure 4 and riveted or otherwise fastened thereto. Said angle pieces 30 have ribs 31 overlapping the sides of the frame jamb 12 and secured by 90 bolts 32 or the like thereto. Similarly, other ribs 33 are formed on angle pieces 30 and overlap the terminal flanges 14 of the frame jamb elements 12 and are secured to said terminal portions 14 and to the terminal 95 portions 24 of the box 23 by bolts 34 or the like.

The provision of the angle pieces 30 fastened as described, strengthens the window frame at the juncture of the sill and 100 jambs.

The sash pulleys 35 as will be clear from Figure 2 are disposed in planes oblique to the medial plane of the window and converge toward a point approximately central 105 of the box 23 so that the sash chains 36 will hang pendent on a line nearly central of the sash weight boxes. The weights 37 of the respective sashes are disposed one above another in vertical alignment or tandem, the 110 alining weights having movement in one box 23 which therefore has an area only slightly larger than that of a single weight. Each of the two alining sash weights in a box 23 has movement at a point from a 115 horizontal line adjacent the sash to a point below the sash.

It is to be understood that in connecting the head 10 with the weight boxes 23 substantially the same construction is provided as with respect to the sill, 11, the down-turned portion 28 being formed from the web of the head similarly to the formation of these members from the web of the sill and the described angle pieces 30 being employed at the head as well as at the sill.

The pulley pins 38 are passed through brackets 39, 39^a secured respectively to the intermediate members 13 of the frame jamb elements 12 and to the central web of said 130

jamb elements 12, by screws or other suitable means.

I would state in conclusion that while the illustrated example constitutes a practical embodiment of my invention, I do not limit myself strictly to the exact details herein illustrated, since, manifestly, the same can be considerably varied without departure from the spirit of the invention as defined 10 in the appended claims.

Having thus described my invention, I claim:

1. A window of the class described including a window frame, and a sliding sash 15 therein having its frame formed with channel jamb bars, said bars presenting side flanges of unequal width, the wider flange having an intermediate oblique portion and said window frame presenting guide channels 20 receiving said wider flanges, said oblique portion of the sash bar jamb contacting with the window frame at opposite sides of said guide channels.

2. A window of the class described including a window frame and a sliding sash 25 therein having its frame formed with channel jamb bars, said sash bars each having a flanged form with an intermediate portion oblique to the general plane of said 30 flange.

3. A window including a window frame the jambs of which are composed of channel bars, the sides of said channel bars having intermediate portions of the sides of the 35 channel directed laterally outward transverse to the general plane of the window, said sides having terminal portions at approximately right angles to the intermediate portions and directed towards the sides of 40 the frame.

4. A window of the class described including a sash weight box open at that side adjacent the jamb of the window, a window frame having jamb elements in the form of 45 channel bars, the sides of the channel bars having intermediate portions directed laterally outward transverse to the general plane of the window and having terminal portions directed toward and overlapping the sides 50 of said weight box, sash weight pulleys, and brackets in which said pulleys turn, said brackets secured to said channel jamb bars, one of said brackets being secured to said intermediate portions of the sides of the 55 channel bars and others of said brackets secured to the webs of said channel bars.

5. In a window of the class described, a sash weight box, inner and outer sashes, and weights attached to said sashes, said 60 weights being disposed in vertical alinement in said box.

6. A window including a window frame,

inner and outer sashes slidable in said frame, sash pulleys mounted on said frame and disposed in oblique planes to be convergent in planes at an angle to the general plane of the window, sash weights in vertical alinement, and flexible connections secured to said weights and sashes and running over the respective pulleys. 65 70

7. A window including a window frame, inner and outer sashes slidable in said frame, sash pulleys mounted on said frame and disposed in oblique planes to be convergent in planes at an angle to the general plane of the window, said frame including jamb elements in the form of channel bars, sash pulleys, means on said channel bars in which said pulleys are mounted, said weights, in vertical alinement, and 80 means running over said pulleys and connecting said sash weights with the respective sashes. 75

8. In a window, inner and outer sliding sashes, a weight for each sash, said weights 85 disposed in vertical alinement and means connecting the respective weights with the sashes.

9. In a window of the class described, inner and outer sliding sashes, a sash weight box, 90 sash weights connected with the respective sashes and disposed in vertical alinement in said boxes, said boxes extending below the cylinders for permitting movement of the lower sash weights below the sill. 95

10. In a window of the class described, inner and outer sliding sashes, a weight for each sash, said weights disposed in vertical alinement, window frame jamb elements of channel form in horizontal section, sash 100 weight boxes secured to said frame jamb elements, a sill of channel form, said boxes extending below said sill, the web of the sill conforming substantially to the channel form of said window frame jamb element and said web being turned down in the form of flanges against the sash weight boxes. 105

11. In a window, a window frame having a head and sill of channel form, and jamb elements of channel form, and sash weight boxes secured to said jamb elements and to said head and sill, the webs of said head and sill having portions thereof bent against the sides of the sash weight boxes and secured thereto. 110 115

12. A window of the class described including inner and outer sliding sashes, and sash weights connected respectively with one of said sashes near the top thereof and with the other sash near the bottom, said weights being disposed in vertical alinement. 120

LOUIS LANE.
